T. F. Hutzel

UNITED STATES PATENT OFFICE.

TITUS F. HUTZEL, OF ANN ARBOR, MICHIGAN.

WATER-FRONT FOR STOVES.

SPECIFICATION forming part of Letters Patent No. 398,783, dated February 26, 1889.

Application filed April 12, 1888. Serial No. 270,495. (No model.).

To all whom it may concern:

Be it known that I, TITUS F. HUTZEL, a citizen of the United States, residing at Ann Arbor, in the county of Washtenaw and State of Michigan, have invented a new and useful Water-Front for Stoves or Ranges, of which the following is a specification.

My invention relates to water-fronts or water-backs for heating water in a stove, range, or other fire-place; and my invention consists of the device illustrated in the accompanying drawing and herein described, reference being made to said drawing, which is a perspective view of the device.

A B is a hollow casting, having a passage within from the inlet-pipe C to the end A, which communicates with the clean-out hole F and the outlet-pipe N M. This casting is of the external form shown in outline. The surface H G K L is curved and sloped, so as to facilitate cleaning and prevent the lodgment of dirt and ashes as far as practicable. The inlet-pipe C and the outlet-pipe N M, as well as the plug P to close the clean-out hole F, all screw into brass bushings to facilitate removal, although any or all of these things may be attached to the casting A B by any other suitable device, if desired. This casting A B has but one opening or passage through it, thereby facilitating casting, it having no interior partition, as is required for water-backs of the ordinary form. The clean-out hole F makes the coring for this casting A B much easier. The production of the casting A B is by these means made easier and cheaper.

It is well known that water-backs fill up in the outlet-passage by incrustation and deposit—not in the inlet; also, that in consequence they have to be abandoned, as they will not pass the water through them, and an entirely new water-back substituted at some expense and inconvenience. The outlet-pipe N M takes the place of the said outlet-passage in this water-back. When it becomes incrusted, or otherwise wholly or partially

stopped or clogged, it may be disconnected from the rest of the hot-water piping, disconnected from the casting A B, and cleaned, or a new pipe substituted at a trifling expense 50 or inconvenience.

The outlet-pipe N M and the curved surface H G K L give much additional heating-surface over the old form of water-back. By disconnecting the inlet-pipe C and removing the 55 plug P from the hole F the entire interior passage of the casting A B is made accessible for cleaning. There is no provision of this kind in common water-backs.

The operation of my invention is as follows: 60 Water enters the inlet-pipe C at the entrance E, passes along within the casting A B from B to A, returns through the outlet-pipe N M, and passes out of N M at D and into the hot-water system, heated by being in contact with 65 the hot iron of the casting A B and the outlet-pipe N M.

I disclaim any intention of resting my invention upon the sizes, adjustment, or manner of connecting the parts of my device, or 70 upon the kinds of materials used in its construction, as these are not essential to its completeness.

What I claim as my invention, and desire to 75 secure by Letters Patent, is—

A water-back casting, A B, as shown, with a curved and sloping surface, H G K L, which is adapted to have the outlet-pipe N M of the water-back pass in front of it, with an offset at the end A, as represented, for receiving this 80 outlet-pipe N M, a clean-out hole, F, to facilitate cleaning and molding said casting A B, with its closing device, as the plug P, and an inlet for the pipe C, in combination with the said outlet-pipe N M, detachably secured, 85 for the purposes specified, as shown and described.

TITUS F. HUTZEL.
